CARTON FILLING MACHINE

Eugene A. Wahl, Garden City, N. Y., and Wilhelm Boehl, Union, N. J., assignors to P. Ballantine & Sons, Newark, N. J., a corporation of New Jersey

Application August 10, 1950, Serial No. 178,646

23 Claims. (Cl. 53—22)

1

This invention relates to carton filling machines, and has particular reference to a machine for inserting cans or equivalent containers of the type which have chimes at their ends, into cartons of the type which are open at their ends and which have tongues inturned from the ends of their top and bottom walls for edge engagement with the chimes of the two end containers of a row in a carton to retain all of the containers of the row in the carton.

Generally speaking, the object of the invention is to provide a practical machine for the purpose stated which is continuous, rapid and reliable in operation.

Cartons of the type referred to usually are furnished by the manufacturer in collapsed, substantially flat condition with their tongues extending outwardly from and lying in the planes of the top and the bottom walls of the cartons. Therefore, it is necessary to set up or erect the cartons into rectangular form and to inturn the tongues relative to the top and bottom walls before inserting the containers into the cartons. Accordingly, a special and important object of the invention is to provide a machine for the purpose stated which includes a magazine to contain the cartons in collapsed condition and which further includes means for ejecting the cartons singly from said magazine and erecting them and inturning their tongues preparatory to filling them with containers.

Another special and important object of the invention, particularly from the viewpoint of providing for continuous and therefore rapid operation of the present machine, is to embody in said machine an endless series of pocket elements which travel continuously in an endless path and successively receive and have erected therein cartons ejected from the magazine, and further to embody in said machine simple, practical means, operable in response to advance of the pocket elements along said path, to insert containers into the cartons contained in said pocket elements.

In packages such as are produced by the present machine, the cartons and the containers contained therein are of substantially the same height. Therefore, it is impractical to insert the containers into the cartons through the open ends of the cartons while the containers are disposed parallel to the ends of the cartons, because of the lack of sufficient clearance between the ends of the containers and the top and the bottom walls of the cartons to permit insertion of the containers without danger of one or the

2

other of the end portions of the containers engaging the edge of one or the other of the carton top and bottom walls and crushing such wall inwardly. A more practical and sure manner of inserting the containers without danger of crushing either the top or the bottom walls of the cartons is first to enter the containers at one end cornerwise into the cartons and then, while gradually moving the containers into the cartons, to gradually bring them into positions parallel to the ends of the cartons while simultaneously shifting them longitudinally to spring one or the other of the carton top and bottom walls outwardly to permit the other ends of the containers freely to enter the cartons. Accordingly, another special and important object of the invention is to provide a machine which is operable to insert the containers into the cartons in the manner just stated.

Another object of the invention is to provide simple, practical means for positively ejecting the filled cartons from the pocket elements.

Another object of the invention is to provide simple, practical means to automatically stop the machine in the event the machine should, for any reason, fail to insert containers into any given carton.

It has been found that most positive and effective cooperation between the carton tongues and the container chimes to insure retention of the containers in the cartons is attained by deflecting the tip portions of the tongues relative to the tongues proper so that the edges of said tip portions engage the container chimes at the bases of the latter. Accordingly, another special and important object of the invention is to provide a machine for the general purposes stated with simple, practical means for deflecting the tip portions of the tongues relative to the tongues proper for the purpose stated.

With the foregoing and various other objects in view, as will become more fully apparent as the nature of the invention is better understood, the same consists in a carton filling machine embodying the novel features of construction, combination, and arrangement of parts and mechanisms as are illustrated by way of example in the accompanying drawings and which will hereinafter be more fully described and claimed.

In the accompanying drawings, wherein like characters of reference denote corresponding parts in the different views:

Figure 33 is a fragmentary section through a package of the type produced by the present invention when the tip portions of the carton tongues are deflected relative to the tongues proper; and

Figure 34 is a perspective view in collapsed condition of a carton of the type with which the present machine is concerned.

In order that the purpose and, hence, the construction and mode of operation of the present machine may be more readily understood as the description of the same proceeds, attention first is invited to Figure 31 of the drawings which illustrates a package of the type produced by the machine. This package, it will be observed, consists of a carton designated generally as A, containing a plurality of containers, designated generally as B.

The containers B are in the form of cans or their equivalents such as are used to contain beer or other beverages, vegetables, fruits, soups or the like, and are characterized by having at their ends rims or chimes b, in which connection see also Figures 32 and 33 of the drawings.

The carton A is open at its ends and is composed of front and rear side walls 10 and 11, respectively, top and bottom walls 12 and 13, respectively, and tongues 14 constituting end extensions of said top and bottom walls.

The carton A is of an internal height corresponding substantially to the height of the containers B and is of a width corresponding substantially to the diameter of said containers. Therefore, the containers are disposed in the carton in a single straight row in side to side relationship to each other. In this connection the carton may be of a length to accommodate only two of the containers, or it may be of any desired greater length to accommodate three or more of the containers. In the present instance, it is illustrated as being of a length to accommodate three of the containers, which is a suitable number to embody in a package.

The length of the carton A is such, with reference to the length of a row of containers which it is designed to contain, that approximately one-half of each of the two end containers of the row projects beyond the related end of the carton.

The tongues 14 are inturned to underlie and overlie the carton top and bottom walls 12 and 13, respectively, and they are of lengths approximately equal to one-half the diameters of the containers B. Upon being inturned, said tongues do not lie flatly against the carton top and bottom walls, but tend to spring away from said walls. Therefore, they spring into the recessed top and bottom portions of the two end containers of a row disposed in the carton and their free edges come to rest against the inner faces of the inner half portions of the chimes b of the two end containers of the row, thereby locking the two end containers against removal from the carton and, hence, holding the entire row of containers in the carton.

All portions of each tongue 14 may be disposed in the same plane, as illustrated in Figure 32 of the drawings. On the other hand, the tip portion 14a of each tongue may be and preferably is deflected relative to the tongue proper so as to extend at an inward inclination to the tongue proper when the tongue is inturned, as illustrated in Figure 33 of the drawings, thus to insure most effective holding contact of the free edges of the tongue tips with the container chimes adjacent to the bases of the latter.

The cartons A are supplied by the manufacturer in collapsed, substantially flat form with one of the side walls and one of the top and bottom walls overlying the other side wall, and

the other of the top and bottom walls, and with the tongues 14 extending outwardly from the ends of the top and the bottom walls in the planes of said top and bottom walls, as illustrated in Figure 34 of the drawings. Therefore, the function of the present machine is, generally speaking, first to set up or open the cartons, then to inturn or partly to inturn the tongues 14, and then to insert the containers into the cartons through their open ends; also, to deflect the tips of the tongues should this be desirable.

Referring now to the drawings of the machine, it will be observed that the machine comprises a main frame, designated generally as F, which appropriately may be composed, as shown, of right and left hand side plates 15 and 16, respectively, suitably connected rigidly together in suitably spaced relationship to each other as, for example, by means of cross rods 17. In addition, the machine includes a housing, designated generally as H, which is suitably secured rigidly to the front end of the main frame F as, for example, by means of bolts 18.

Extending transversely of the main frame F are two horizontal shafts 19 and 20 which are supported at or near their ends in suitable bearings carried by the side plates 15 and 16 and which are disposed in a common horizontal plane near the top of said main frame and adjacent to its front and rear ends, respectively.

The front shaft 19 preferably is non-rotatable and has rotatably mounted thereon a sprocket wheel 21. If desired, however, said shaft 19 may be rotatable and the sprocket wheel 21 may be fixed thereto for rotation therewith. In any event, the rear shaft 20 is rotatable and has fixed thereto for rotation therewith a sprocket wheel 22.

The sprocket wheels 21 and 22 are disposed in the central, vertical, longitudinal plane of the machine and are connected together by an endless sprocket chain 23 to which is suitably secured, at evenly spaced intervals therealong, an endless series of pocket elements 24.

The pocket elements 24 extend outwardly from the sprocket chain 23 and are duplicates of one another, each being of substantially U-shape in cross section, open at its sides and top and being composed of a bottom wall 25 and front and rear walls 26 and 27, respectively. Said pocket elements are of internal widths, lengths and heights corresponding substantially to the widths, lengths and heights of the cartons A when the latter are in set up or open condition.

At the inner sides of the main frame side plates 15 and 16 are track members 28, 29 which are right and left hand duplicates of each other and which may be of any suitable form for cooperation with the pocket elements 24 in any suitable manner to guide said pocket elements for movement in a horizontal plane, parallel to the top of the main frame F, during travel of said pocket elements with the upper reach 23a of the sprocket chain 23. In the drawings, said track members are illustrated as being separate from and bolted rigidly to the side plates 15 and 16 and as having therein guide channels 29, the end portions of which are concentric with the shaft 19 and 20 and the medial portions of which are straight and disposed parallel to the top of the main frame F. At the sides of the pocket elements 24 are pairs of rollers 30 which travel in said channels 29 and thus not only insure straight line movement of said pocket elements as they travel with the upper reach 23a of the sprocket chain

23, but, during such travel of said pocket elements, serve to maintain them in upright positions.

Above and cooperating with the lower reach 23b of the sprocket chain 23 to take up any slack in said chain, is a suitable chain tightener 31.

Mounted upon the top of the housing H, adjacent to the front end of the main frame F, is a suitable magazine, designated generally as 10 M, to contain a stack S of the cartons A in collapsed condition with the cartons disposed transversely relative to the machine, as best illustrated in Figures 4 and 10 of the drawings. The magazine M may be of any suitable design and is illustrated in the drawings as comprising a pair of laterally spaced castings 32 bolted to the top of housing H, front and rear cross bars 33 and 34, respectively, connecting said castings and rising therefrom, a front pair of uprights 35 bolted to the front cross bars 33 and rising therefrom, a single, medially disposed upright 36 bolted to the rear cross bars 34 and rising therefrom, and side pairs of uprights 35' bolted to and rising from the castings 32.

Also mounted upon the top of the housing H, between the castings 32, is a pair of laterally spaced, horizontally disposed bars 37 which extend longitudinally of the machine and upon which the stack S of cartons rests.

30 During operation of the machine, the upper reach of the sprocket chain 23 travels toward the rear end of the machine. Hence, the pocket elements 24 travel upwardly and rearwardly around the front sprocket wheel 21. In this connection, the vertical disposition of the bars 37 is suitably above the horizontal plane of the shafts 19 and 20 to support the stack S of cartons A so that said cartons may be fed successively rearwardly from the bottom of said stack individually into the successive pocket elements 24 through their open tops during the latter half of their travel upwardly and rearwardly around the sprocket wheel 21.

45 Additionally mounted upon the top of the housing H for sliding movement longitudinally of the machine is a carton pusher bar 38 which is disposed horizontally and which is reciprocable between a position in which its rear end is disposed slightly forwardly of the stack of cartons A in the magazine M and a position in which its rear end is disposed adjacent to the path followed by the upper edges of the front and the rear walls of the pocket elements 24 as said pocket elements travel around the front sprocket wheel 21.

55 The pusher bar 38 is slidable between the bars 37 and its vertical disposition is such that it may pass freely beneath the lowermost carton A of the stack S when said lowermost carton is not medially deflected downwardly, but is engageable at its rear edge with the front edge of the lowermost carton of said stack to push said lowermost carton rearwardly from said stack when said lowermost carton is medially deflected downwardly as shown in Figure 9 of the drawings.

60 Mounted upon the pusher bar 38 for reciprocation with respect thereto longitudinally of the machine is a blade 39 which, when the lowermost carton A of the stack S has been medially deflected downwardly, is designed to enter between said lowermost carton and the carton immediately thereabove to maintain said lowermost carton medially deflected downwardly and to relieve said lowermost carton of the weight of the stack 70 of cartons thereabove while said lowermost car-

ton is being pushed from the bottom of the stack S by the pusher bar 38.

Mounted upon a side wall 40 of the housing H is a bearing 41 in which is mounted for vertical reciprocation a rod 42 which, at its upper end, carries a vacuum head 43 which includes one or more vacuum cups 44. The said vacuum cup, or cups, open upwardly and is, or are, disposed directly beneath the magazine M for cooperation with the lowermost carton A of the stack S to 10 medially deflect said lowermost carton downwardly. In this connection, in order to permit the vacuum cups 44 to engage the lowermost carton A when the pusher bar 38 is projected, the rear end portion of said pusher bar is bifurcated or 15 slotted as will be noted by reference to Figures 4 and 8 of the drawings.

In suitable bearings carried by the side walls 40 of the housing H is rotatably mounted a horizontal shaft 45 which extends transversely of said housing near the bottom thereof and has fixed thereon two eccentric wheels 46 and 47 and a cam wheel 48.

A second horizontal shaft 49 extends transversely of the housing H forwardly of the shaft 45 and is suitably mounted in the side walls of said housing and has pivoted thereto, at their lower ends, for forward and rearward swingable movement, two levers 50 and 51, which, at their upper ends, are connected by links 52 to the blade 39 and the pusher bar 38, respectively.

Straps 53 embrace the eccentric wheels 46 and 47 and are connected by links 54 to the levers 50 and 51, respectively. Thus, rotation of the shaft 45 and the eccentric wheels 46 and 47 is effective to rock the levers 50 and 51 and thereby reciprocate the blade 39 and the pusher bar 38.

The cam wheel 48 is provided with a cam channel 55 in which operates a cam follower in the form of a roller 56 carried by the rod 42, and said cam channel is of a form such that it serves to raise and lower the rod 42 and, hence, the vacuum head 43 and the vacuum cup, or cups, 44 once during each complete rotation of said cam wheel 48 with the shaft 45.

Extending transversely of the main frame F at a suitable location is a fixed horizontal shaft 57 which is suitably supported at its ends by the side plates 15 and 16 and which has rotatably mounted thereon a sprocket wheel 58 to which is fixed, for rotation therewith, a smaller sprocket wheel 59 which is connected by a sprocket chain 60 to a sprocket wheel 61 fixed on the rear shaft 20.

An electric motor 62 for driving the machine is mounted at a suitable location on the machine as, for example, at the bottom of the main frame F, and operates through a speed reduction gearing, designated generally as 63, to drive a sprocket wheel 64.

Connecting the sprocket wheel 64 with the sprocket wheel 58 and also with a sprocket wheel 65 fixed to the shaft 45 is an endless sprocket chain 66. Thus, operation of the motor 62 is effective to drive the shaft 20 and, hence, the sprocket chain 23 and the pocket elements 24 carried thereby and, at the same time, to drive the shaft 45.

Mounted at a suitable location in the housing H is a solenoid valve 67 which is connected by a flexible tube 68 to the vacuum head 43 and by a pipe 69 to a suitable source of negative pressure air, such as a vacuum pump 70 mounted on the housing H at the bottom thereof, and which is effective to control communication between said

source of negative pressure air and the vacuum cup, or cups, 44.

Also mounted at a suitable location in the housing H is an electric switch 71 which is geared to the shaft 45, as indicated at 72, for operation in definitely timed relationship to rotation of said shaft 45 and which is suitably connected to the solenoid valve 67 for controlling operation thereof.

Since the cartons A are to be delivered successively from the bottom of the stack S individually to the successive pocket elements 24, and since one carton is delivered from said stack during each complete rotation of the shaft 45, the speed of travel of the sprocket chain 23 and the pocket elements 24 relative to the shaft 45 is arbitrary and depends, of course, upon the spaced relationship of the pocket elements 24 relative to each other along said sprocket chain 23. In any event, the gear ratio between the sprocket chain 23 and the shaft 45 is such, depending upon the spacing of the pocket elements 24 along said sprocket chain, that as each pocket element 24 moves through a predetermined angle during the latter half of its travel upwardly and rearwardly around the sprocket wheel 21, a carton A is delivered thereto from the bottom of the stack S.

In the foregoing connection, the positions of the eccentric wheels 46 and 47 and the cam wheel 48 angularly relative to the shaft 45 and relative to each other, and the timing of operation of the solenoid valve 67 by the switch 71, are such that as the blade 39 and the pusher bar 38 are moved forwardly or retracted, the vacuum head 43 is moved upwardly to engage the vacuum cup, or cups, 44 against the underside of the lowermost carton A in the stack S. Then, when the rear end of the blade 39 is disposed forwardly of the magazine M, the switch 71 is actuated to operate the solenoid valve 67 to connect the vacuum cup, or cups, 44 with the source of negative pressure air and thus cause said vacuum cup, or cups, to adhere to the lowermost carton A. Immediately thereafter the vacuum head 43 is moved downwardly to effect downward deflection of the medial portion of the lowermost carton. The blade 39 then moves rearwardly or is projected into the space between the downwardly deflected medial portion of the lowermost carton and the carton immediately thereabove and thereafter the switch 71 is actuated to operate the solenoid valve 67 to deny communication between the source of negative pressure air and the vacuum cup, or cups, 44 and to vent the latter, thus releasing the lowermost carton for projection by the pusher bar 38. In the meantime, said pusher bar 38 has completed its forward or retractive movement so that its rear end is disposed forwardly of the downwardly deflected medial portion of said lowermost carton. The pusher bar then moves rearwardly and by engagement of its rear end with the front edge of the said downwardly deflected medial portion of the lowermost carton, serves to push said lowermost carton rearwardly from the bottom of the stack S.

As the lowermost carton A is pushed rearwardly from the bottom of the stack S, a pocket element 24 moves around the sprocket wheel 21 to an upwardly and forwardly inclined position to present its open top to the horizontal plane of rearward movement of said carton. Thus, as the said pocket element 24 moves upwardly and rearwardly during the latter half of its travel around the sprocket wheel 21, the lowermost carton A of the stack S is pushed into said pocket

element. In this connection and as illustrated in Figure 6 of the drawings, the timing of rearward movement of the pusher bar 38 and, hence, of rearward movement of the lowermost carton A with reference to advance of the pocket elements 24, is such that the rear edge of the lowermost carton reaches the lower, rear corner of a pocket element 24 at approximately the same time as said pocket corner reaches the horizontal plane of said carton. Continued pushing by the pusher bar 38 against the front edge of the carton and which is at a rate greater than the recessive or rearward movement of said pocket corner due to its circular path of travel, therefore results in endwise pressure upon the carton to effect opening of the same. However, in the absence of means to insure positive initial opening of the carton, the said endwise pressure might result in bowing of the carton either upwardly or downwardly with consequent failure of the same to open. Accordingly, means is provided to initiate positive opening of the carton either immediately before or at about the same time as the beginning of the endwise pressure against the same so as to insure its proper subsequent further opening by such pressure.

The means just referred to comprises a pair of rocker elements 13, 13 which are right and left hand duplicates of each other and which are disposed at opposite sides of the latter half of the upward and rearward path of travel of the pocket elements 24 around the sprocket wheel 21. Each rocker element includes a horizontal shaft 14 which extends transversely of the machine and is rockably mounted in a suitable bearing 15 carried by the related side plate of the main frame F, and further includes two pins 16 and 17 which extend inwardly for cooperation with the tongues 14 of a carton A disposed approximately as shown in Figure 6 of the drawings in readiness to be initially opened either immediately prior to or at about the same time as it is subjected to endwise pressure by the pusher bar 38.

As delivered from the magazine M in collapsed, substantially flat condition, each carton A has its bottom and front side walls 13 and 10, respectively, underlying its rear side and top walls 11 and 12, respectively, with its bottom wall disposed rearwardly and its top wall disposed forwardly so that the carton is properly openable into a pocket element 24 by downward and rearward swinging movement of its bottom wall and upward and forward swinging movement of its top wall. The pins 16 and 17, by engagement with the tongues 14 and by their swinging movements, due to rocking of the rocker elements 13, are designed to initiate said swinging movements of said carton walls. Accordingly, when a carton is disposed substantially as shown in Figure 6 of the drawings, the rocked positions of the shafts 14 are such that the pins 16 overlie the tongues 14 of the carton bottom wall 13 and the pins 17 underlie the tongues 14 of the carton top wall 12. Thus, by rocking of said shafts 14 from their said positions in directions to swing the pins 16 downwardly and the pins 17 upwardly, said pins act upon the tongues 14 to swing the carton bottom and top walls positively in directions to open the carton.

Any suitable means may be provided to rock the rocker elements 13. For example, as shown in the drawings, the shaft 45 may have fixed thereto a pair of cam wheels 78 for rocking a pair of levers 79 which may be suitably pivoted to the housing H, and said levers 79 may be con-

nected by links 80 to lever arms 81 on the shafts 14. In this connection the design of the cam wheels 78 is, of course, such that the rocker elements 13 are rocked at the proper times to accomplish their carton opening purpose, and the amplitude of their rocking movements in directions to open a carton is such that as a carton is opened the pins 16 and 17 progressively move to positions, substantially as shown in Figure 7 of the drawings, to permit the tongues 14 to pass by the same. Additionally, the design of the cam wheels 78 is such that immediately after the tongues 14 of an opened carton have moved past the pins 16 and 17, the rocker elements 13 are returned to a starting position to dispose said pins 16 and 17 respectively above and below the plane of delivery of the next carton from the bottom of the stack S in readiness to open said next carton after it has been projected into the next pocket element 24.

Suitably mounted on the housing H and extending rearwardly therefrom at opposite sides of the path of travel of the pocket elements 24 is a pair of arms 82, 82 over which slide the inner portions of the tongues 14 of each lowermost carton A as it is pushed from the bottom of the stack S. Said arms thus serve to support the cartons as they are delivered from the magazine M and prior to their erection in the pocket elements 24.

Extending upwardly and rearwardly from the lower, rear portion of the magazine M to a point nearly to a vertical, transverse plane which includes the axis of the shaft 19, is an arcuate member 83 the under surface of which extends concentrically to said shaft and is disposed to engage the top wall 12 of an opened carton A in each pocket element 24 during travel of each pocket element and carton upwardly and rearwardly over the sprocket wheel 21. Thus, during such travel of each pocket element and carton, said member 83 functions to maintain the carton in open condition in the pocket element.

Consisting, in effect, a continuation of the member 83 to engage the tops of the cartons A and to maintain the cartons in open condition in the pocket elements 24 as the latter travel rearwardly with the upper reach 23 of the sprocket chain 23, is a horizontal bar 84 which extends longitudinally of the machine at a proper elevation above the top of the main frame F and which is substantially coextensive in length with the said upper reach of said sprocket chain. Appropriately, said bar 84 may be mounted upon suitable cross members 85 supported by posts 86 rising from the main frame side plates 15 and 16.

While the member 83 may be fixed with respect to the machine, it preferably is removable to afford ready access to the pocket elements 24 whenever such access may, for any reason, be desired. In this connection and as shown in the drawings, said member may be removably mounted by engagement of a recess, or recesses, in its front end with a pin, or pins, 87 carried by a lower, rear cross bar 33 of the carton magazine M, and by resting at its rear end upon the rear cross member 85 and being latched to said rear cross member as indicated at 88.

To assist the pusher bar 38 and the rocker elements 13 in effecting final opening of the cartons A and to insure complete opening of said cartons before they pass under the arcuate member 83, a pair of arms 89, 89 are provided. These arms are disposed substantially vertically at opposite sides, respectively of the arcuate member 83 and at their upper ends are suitably pivoted for for-

11

ward and rearward swinging movements about an axis suitably located above the path of upward and rearward travel of the pocket elements 24 around the sprocket wheel 21. Appropriately said arms may be pivoted by being fastened at their upper ends to a horizontal, transversely extending shaft 90 rotatably mounted in a bracket 91 fastened to and extending rearwardly from an upper, rear cross bar 33 of the magazine M. In any event, said arms are of lengths such that when they are swung rearwardly, their lower end portions are engageable at their rear edges with the top wall 12 of a carton A almost completely opened in a pocket element A, to completely open said carton and to maintain it completely open during its upward and rearward travel around the sprocket wheel 21 until its said top wall has moved into underlying relationship to the arcuate member 83.

Any suitable means may be provided for swinging the arms 89, 89. In this connection and as illustrated in the drawings, a lever arm 92 is fixed to and depends from the shaft 90 and at its lower end is connected by a link 93 to one arm of a two-arm lever 94 which is suitably pivoted intermediately to the housing H, as indicated at 95, and which has its other arm suitably cooperating with a cam wheel 96 fixed on the shaft 45.

The design of the cam wheel 96 is, of course, such that it acts at proper times through the lever 94, the link 93 and the lever arm 92 to swing the arms 89, 89 forwardly to positions substantially as illustrated in Figure 6 of the drawings to dispose their lower end portions forwardly of the top wall 12 of a carton A being opened into a pocket element 24 as the latter travels upwardly and rearwardly around the sprocket wheel 21, and to swing said arms quickly rearwardly just prior to the time when the upper, front corner of the carton is about to move above the rear end of the pusher bar 38.

The rear edges of the lower portions of the arms 89, 89 have either the same curvature as the underside of the arcuate member 83, or are otherwise suitably contoured so that they act, when said arms are swung rearwardly, to engage the top wall 12 of a nearly completely open carton A in a pocket element 24 traveling upwardly and rearwardly around the sprocket wheel 21 and to exert rearward pressure upon the carton to completely open it in said pocket element and to maintain it completely open until its top wall is engaged beneath the underside of the arcuate member 83.

Suitable means is provided for operation following delivery to and opening of a carton A in each pocket element 24, to initiate inturning of the carbon tongues 14. According to the embodiment of the invention illustrated in Figures 1 to 24 of the drawings, said means comprises an upper pair of cam plates 97, 97 mounted on the arcuate member 83 and a lower pair of cam plates 98, 98 mounted on the tops of the front end portions of the track members 28, 28. The cam plates of each pair are right and left hand duplicates of each other and are disposed at opposite sides, respectively, of the final portion of the upward and rearward path of travel of the pocket elements 24 around the sprocket wheel 21. The front portions of the upper plates 97, 97 are disposed horizontally in positions to have the tongues 14 of the carton top walls 12 pass beneath them. On the other hand, the rear portions of said upper plates are disposed vertically, closely

12

adjacent and in overlying relationship to the path of travel of the upper side portions of the pocket elements 24. Between their said front and rear portions said upper plates are spirally twisted so that as each pocket element 24, with an open carton A therein, completes its upward and rearward travel around the sprocket wheel 21, they act to wipe the tongues 14 of the carton top wall downwardly to positions at substantially right angles to the carton top wall. Similarly, the front portions of the lower plates 98, 98 are disposed horizontally, but in positions to have the tongues 14 of the carton bottom walls 13 pass over them, and the rear portions of said lower plates are disposed vertically, closely adjacent and in overlying relationship to the path of travel of the lower side portions of the pocket elements 24. Between their said front and rear portions said lower plates also are spirally twisted so that as each pocket element 24, with an open carton therein, completes its upward and rearward travel around the sprocket wheel 21, they act to wipe the tongues 14 of the carton bottom wall upwardly to positions at substantially right angles to the carton bottom wall.

In accordance with the invention, the containers B are inserted or fed into the open cartons A contained in the pocket elements 24, through the open ends of said cartons, in response to rearward travel of said pocket elements with the upper reach of the sprocket chain 23.

At opposite sides of the path of travel of the pocket elements 24 with the upper reach 23a of the sprocket chain 23, near the front end of said path of travel, are magazines 99, 99, respectively, to which containers B are continuously delivered in any suitable manner from any suitable source of supply. Said magazines are mounted on the tops of the main frame side plates 15 and 16, respectively, and may be aligned or disaligned transversely of the machine, as desired. They are right and left hand duplicates of each other and each includes front and rear walls 100 and 101, respectively, a bottom wall 102, and a top wall 103. They may be of any suitable lengths, extend transversely of the machine, and in internal widths and heights correspond substantially to the diameters and heights, respectively, of the containers B. They are open at their outer ends 40 for delivery of containers into the same and have their inner ends disposed adjacent to the planes of the sides of the pocket elements 24. In the inner ends of the rear walls of said magazines are exit openings 104 through which the containers B may be moved rearwardly, one at a time, from said magazines.

Carried by the front wall 26 of each of the pocket elements 24 and projecting beyond the sides of said wall are container pusher arms 105 which are effective, as the pocket elements 24 move successively past the inner ends of the magazines 99, to engage the innermost containers B in said magazines and push them rearwardly through the exit openings 104 in the rear walls of said magazines. In other words, as each pocket element 24 passes the magazines 99, it acts through its pusher arms 105 to pick up one container B from each of said magazines and to move the two picked-up containers along therewith at opposite sides thereof, respectively. In this connection, it will be noted that the rear sides of the pusher arms 105, which engage the containers B, are disposed approximately in the planes of the inner or rear faces of the front walls 26 of the pocket elements 24, thus to posi-

tion the containers B in alignment with said pocket elements so that they may be pushed directly inwardly into cartons A contained in said pocket elements.

The inner end portions of the front walls 109 of the magazines 99 are, of course, suitably recessed, as indicated at 106, for passage of the pusher arms 105 through them to pick up the innermost containers B in said magazines.

The two magazines 99 provide, of course, for supply of two containers to each of the cartons A. In this connection, each carton may, as aforesaid, be designed to hold only two containers, in which event there is no necessity of providing an additional magazine, or magazines, for supply of an additional container, or containers, to each carton. On the other hand, each carton may, as aforesaid, be designed to hold three or more containers, in which event there may be provided, rearwardly of the magazines 99, as many similar additional magazines as may be required to supply the desired number of containers to each carton. In the present instance each carton is designed to hold three containers. Therefore, there is provided, in addition to the two magazines 99, 25 a single similar additional magazine, designated generally as 107, which is disposed rearwardly of an in suitably spaced relationship to one of the magazines 99 to supply a third container to each carton.

Extending rearwardly from each of the magazines 99, 99 and 107, along the related side of the path of travel of the pocket elements 24 with the upper reach 23^a of the sprocket chain 23 is a guide means for containers B being moved along said path of travel with said pocket elements. Said guide means are designated generally as G', G² and G³, respectively, and are operable, responsive to movement of said pocket elements and the containers along said path of travel, to insert the containers into cartons contained in said pocket elements. To that end, each of said guide means comprises inner, outer and intermediate top rails 108, 109 and 110, respectively, and inner, outer and intermediate bottom rails 111, 112 and 113, respectively. At or adjacent to their front ends the rails of each of said guide means are fastened to their related magazine, while rearwardly of their related magazine they are fastened to and are supported by suitable brackets 114 mounted upon the tops of the main frame side plates 15 and 16 at locations suitably spaced therealong.

The intermediate bottom rails 113 serve as track rails or supports upon which the containers B rest and along which they are slidably, while the intermediate top rails 110 overlie containers resting upon the related intermediate bottom rails 113 and serve to hold the containers against rising from said intermediate bottom rails.

The inner, top rails 108 are straight and extend parallel to the planes of the sides of the pocket elements 24 closely adjacent to said planes. At the side of the machine where there is only a single container magazine, there is only a single inner, top rail 108, and this rail is substantially coextensive in length with the path of travel of the pocket elements 24 with the upper reach 23^a of the sprocket chain 23. At the side of the machine where there are the two container magazines, there are, of course, two inner, top rails 108, and collectively these rails are substantially coextensive in length with the path of travel of the pocket elements 24 with the upper reach 23^a of the sprocket chain 23.

The inner, bottom rails 111 may be of any suitable lengths and are straight and from the container magazines are inclined rearwardly and inwardly approximately to the planes of the sides of the pocket elements 24.

At the side of the machine where there is only a single container magazine, there is only a single outer, bottom rail 112 which is substantially coextensive in length with the path of travel of the pocket elements 24 with the upper reach 23^a of the sprocket chain 23. On the other hand, at the side of the machine where there are the two container magazines, there are, of course, two outer, bottom rails 112 which are related respectively, to said magazines. Of these two outer, bottom rails, the front one has its rear end disposed suitably forwardly of the container magazine 107 and the rear one extends from the container magazine 107 approximately to the rear end of the path of travel of the pocket elements 24 with the upper reach 23^a of the sprocket chain 23.

The outer top and bottom rails 109 and 112, respectively, are disposed to engage the outer top and bottom portions, respectively, of containers B and serve as cam rails not only to urge the containers B into cartons A in the pocket elements 24, but to tilt the containers from upwardly and inwardly inclined positions to vertical positions as the pocket elements 24 and the containers move rearwardly from the container magazines. To this end, the outer bottom rails 112 extend parallel to the inner bottom rails 111 so as constantly to urge the bottom portion of the containers inwardly, while the outer top rails 109 first are inclined rearwardly and inwardly parallel to the bottom rails 111 and 112 so as to act initially to urge the top portions of the containers inwardly into the cartons and then, for suitable distances rearwardly, extend parallel to the planes of the sides of the pocket elements 24 so as not further to urge the top portions of the containers inwardly, but to maintain the said container top portions entered in the cartons. Since the bottom portions of the containers constantly are urged inwardly by the outer bottom rails 112, it therefore follows that as the containers are advanced following insertion of their upper corners into the cartons, they gradually are tilted to vertical positions with consequent insertion of their bottom portions into the cartons.

Rearwardly from the locations along the lengths of the guide means G', G² and G³ where the containers finally are tilted to vertical positions, the outer top and bottom rails 109 and 112 are correspondingly inclined more or less sharply rearwardly and inwardly to effect more or less quick final insertion of the containers into the cartons while the containers are disposed vertically and during a more or less short amount of rearward travel of the containers and the cartons. In this connection, it will be noted by reference to Figure 5 of the drawings that at the side of the machine where there are the two container magazines, the said more or less sharply inclined portions of the outer top and bottom rails of the guide means which are related to the front container magazine, extend inwardly to the plane of the adjacent sides of the pocket elements 24 so as to effect complete insertion of the containers into the pocket elements. This, of course, is to insure against any possibility of the containers first inserted at this side of the machine from projecting beyond the related sides of the pocket elements 24 and possibly interfering with travel 75 of said pocket elements past the container maga-

zine 107. On the other hand, it will be noted that the said more or less sharply inclined portions of the outer top and bottom rails of the remaining two guide means extend only sufficiently inwardly to effect insertion of approximately only one-half portions of the containers into the cartons. In this connection, containers inserted by the guide means G³ related to the container magazine 107 serve, of course, to push the containers previously inserted at the same side of the machine to their final positions medially of the cartons.

As previously stated, the height of the containers B is approximately equal to the internal height of the cartons A. Therefore, it is impracticable to insert the containers into the cartons while the containers are disposed parallel to the ends of the cartons. A more practical manner of inserting the containers is to initially enter them cornerwise into the containers and then finally to enter them by tilting them to positions parallel to the ends of the cartons. Accordingly, the bottoms of the magazines 99, 99 and 107 are inclined downwardly and inwardly, and the rails of each of the guide means G', G² and G³, adjacent to their related magazine, are arranged so that the containers B, as they are moved rearwardly from said magazines, are presented in upwardly and inwardly inclined relationship to the open ends of the cartons A with their upper, inner corners disposed sufficiently below the top walls 12 of the cartons so that they may pass freely inwardly beneath said top walls (see Figures 15 and 16 of the drawings).

Each of the inner top rails 108 includes a portion 115 (see Figures 11 and 12) which is disposed at the inner end of the related container magazine in the path of inward movement of the top portions of containers in the magazine so as to serve as a stop element to prevent the upper, inner corner of the innermost container in the magazine from entering a carton in a passing pocket element 24 until the said innermost container has been picked up by the pocket member and thereby alined with the carton. However, directly rearwardly of its portion 115, the lower edge of each of the inner top rails 108 is stepped upwardly, as indicated at 116, to permit the upper, inner corner of a rearwardly and inwardly moving container to pass inwardly beneath said edge and to enter the carton.

Each of the inner bottom rails 111 includes a portion 117 which extends from the inner end of the related container magazine a suitable distance rearwardly and which is disposed in the path of inward movement of the bottom portion of a container being moved rearwardly and inwardly along the related guide means so as to serve as a stop element to prevent the lower portion of the container from entering the carton with which the container is alined. However, at the rear end of its portion 117, each inner bottom rail 111 has its upper edge stepped downwardly, as indicated at 118, to permit the bottom portion of a rearwardly and inwardly moving container to pass over said edge and enter a carton with which it is alined.

Each inner top rail 108, rearwardly of its stop portion 115, has its lower edge inclined upwardly and rearwardly, as shown in Figures 11 and 12 of the drawings, so that as a container moves rearwardly beneath said edge it may rise to bring its lower, inner corner to an elevation to freely enter the bottom portion of a carton with which it is alined. In this connection, the upper edges of the

downwardly stepped portions of the inner bottom rails are suitably inclined rearwardly and upwardly so that as a container continues to move rearwardly after having had its upper, inner corner inserted into a carton, and as the container is tilted toward a vertical position, it is raised sufficiently to permit its lower, inner portion freely to enter the carton. During such raising of the container the end portion of the carton top wall 12 is sprung upwardly (see Figures 17, 18 and 21) to afford clearance between the bottom wall 13 of the carton and the bottom of the container. However, rearwardly from the points where the bottoms of the containers enter the cartons, the arrangement of the rails of each of the guide means is such as to hold the containers vertically and in substantially exact alinement vertically with the cartons.

As will be apparent, as containers from the magazines 99, 99 are urged cornerwise into a carton, the upper, inner corners of the containers will engage the downwardly turned tongues 14 of the top wall 12 of the carton and infold said tongues into underlying relationship to said top wall.

Since the upper, inner corners of the containers initially engage the tongues of the carton top wall at points materially spaced downwardly from said top wall, the leverage exerted by the container corners upon said tongues is ample to insure proper infolding of the latter. On the other hand, since the lower, inner corners of the containers enter the carton closely adjacent to the bottom wall of the carton, it is considered advisable not to rely upon the lower, inner corners of the containers to effect infolding of the carton bottom wall tongues, but to provide means to infold said bottom wall tongues prior to the time that the containers are inserted into the cartons. Said means may be of any suitable form and in the present machine comprises a pair of horizontally disposed, reciprocable fingers 119 (see Figure 13) which extend transversely of the machine and which are mounted for reciprocation in suitable bearings 120 at opposite sides of the path of travel of the pocket elements 24 with the upper reach of the sprocket chain 23, directly forwardly of the container magazines 99.

Mounted for reciprocation in suitable bearings 121 carried by the side plates 15 and 16 of the main frame of the machine below the fingers 119 are horizontal rods 122 which extend transversely of the machine and which are connected at their outer ends to the outer ends of the fingers 119, respectively, by rocker levers 123 which are pivoted intermediately as indicated at 124. Thus, reciprocation of the rods 122 is effective to reciprocate the fingers 119.

Fixed to the front sprocket wheel 21 for rotation therewith is a pair of cam wheels 125 which have cam channels 126 in which are disposed rollers 127 on the inner ends of the rods 122, whereby said rods and, hence, the fingers 119 are reciprocated responsive to rotation of said sprocket wheel. In this connection, the shape of each of the cam channels 126 is such that the fingers 119 are projected or moved inwardly and then are retracted or moved outwardly during the time that a pocket element 24 is advancing between them.

The fingers 119 are disposed so that when they are projected their inner ends engage the upturned bottom wall tongues 14 of a carton in an advancing pocket element 24 and fold said tongues inwardly and downwardly. Moreover,

the bottoms of the inner end portions of said fingers are disposed so that they act to press said tongues against, or substantially against, the bottom wall of the carton. In addition, due to advance of the pocket element and carton during projection and retraction of the fingers 119, said fingers exert a wiping or ironing action upon the tongues 14. Thus, the bottom wall tongues of the cartons are effectively infolded prior to the time that the containers are inserted into the cartons so that when, subsequently, the bottom portions of the containers are urged into the cartons they enter the cartons freely and easily. After being infolded by the fingers 119, the bottom tongues spring upwardly from the carton bottom walls sufficiently so that in a package as produced by the machine they are effective to perform their locking functions.

As will be apparent from the foregoing, as each pocket element 24 with a carton therein travels rearwardly with the upper reach 23^a of the sprocket chain 23, two containers initially are picked up from the two container magazines 99, 99 and are inserted into the carton through the opposite ends thereof, respectively, and then a third container is picked up from the container magazine 107 and is inserted into the carton, pushing one of the initially inserted containers to a position midway between the ends of the carton.

Preferably, the pocket elements 24 are disposed as closely as practicable to each other along the length of the sprocket chain 23, and preferably the container pusher arms 185 have their rear faces inclined forwardly and inwardly so that the pusher arms of each pocket element assist in guiding containers into the carton contained in the next adjacent forwardly disposed pocket element. To this end, the pusher arms 185 of the pocket elements 24 preferably are of such widths, adjacent to the sides of the pocket elements 24, that during travel of the sprocket chain 23, the pusher arms of each pocket element extend forward substantially to the plane of the inner or front face of the rear wall of the next adjacent forwardly disposed pocket element. Thus, as any pusher arm 185 of any given pocket element 24 picks up a container from any of the container magazines and moves the container rearwardly from such magazine, the next container advancing inwardly to the inner end of the magazine engages the forwardly and inwardly inclined front face of the said pusher arm and by said face is guided into the carton in the next adjacent rearwardly disposed pocket element 24. The pusher arms 185 serve, too, as spacers between adjacent pocket elements 24 to prevent more than one container from being delivered from any given container magazine to any given pocket element during travel of the 60 pocket element past the container magazine.

Ordinarily, the containers are fed to the container magazines at a rate such that, as a container is removed from the inner end of any magazine, the next adjacent container in the magazine simultaneously moves inwardly in the magazine to replace the removed container. In this connection and for one reason or another, there may be times when feeding of the containers to any given magazine may lag and the innermost container may be disposed somewhat outwardly of the inner end of the magazine when it is picked up by the pusher arms 185 of an advancing pocket element 24. Accordingly, means is provided whereby, in such event, the innermost

5 container in the magazine is given an inward thrust to insure its proper entrance into the related container guide means as it is moved rearwardly from the magazine. For each of the container magazines this means comprises a friction roller 128 of any suitable material disposed substantially vertically in a position to engage the outer, rear side portion of the innermost container in the magazine as said innermost container is urged rearwardly from the magazine. Each roller is driven constantly in a direction and at a speed such that, when it is contacted by a container, it exerts a quick, inward and rearward thrust upon the container, thus guiding and urging the container into the related guide means.

20 While the rollers 128 may be driven in any suitable manner, each roller preferably is driven by an electric motor 129 individual thereto and mounted, for example, upon a bracket 130 suitably mounted upon the related container magazine.

25 Due to manufacturing tolerances, the cartons A may vary slightly in height. Therefore, the bar 84 is disposed at an elevation such that the distance between its under face and the top faces of the bottom walls 25 of the pocket elements 24, as the latter travel with the upper reach of the sprocket chain 23, is at least equal to, or, for safety reasons, suitably in excess of the maximum height of any given carton. Consequently, there is a clearance space between the under face of the bar 84 and the top walls of most of the cartons A passing beneath said bar. This clearance space, while small, nevertheless may, in some instances, be sufficiently great that, in the absence of means to prevent upward movement of the cartons relative to the pocket elements 24, the cartons might be bodily 30 lifted in their pocket elements by the containers B as the latter, in entering the cartons, act to flex the end portions of the carton top walls upwardly to afford clearance between the bottoms of the containers and the bottom walls of the cartons for free entrance of the bottom portions of the containers into the cartons. Obviously, if any carton were permitted to be lifted bodily even a small amount from its pocket element 24 during insertion of a container into the carton, the end edge of the bottom wall of the carton might become disposed in the path of inward movement of the bottom portion of the container and in that event, the bottom portion of the container, instead of entering the 35 carton, might engage said edge and crush the carton bottom wall inwardly. Accordingly, means is provided to prevent any lifting of the cartons A from their pocket elements 24 by the containers B to the latter exerting upward flexing force upon the end portions of the top walls of the carton. As illustrated in the drawings, this means comprises a shoe 131 overlying the bar 84 and having flanges 132 extending downwardly therefrom at the sides of said bar 84 for engagement at their bottoms with the top walls of underlying containers B. The shoe 131 extends along that portion of the bar 84 beneath which the cartons A are advanced while the containers A are exerting upward flexing force upon the end portions of the carton top walls 12, and the flanges 132 are of depths to extend amply below the bottom face of the bar 84 to engage the top walls of cartons of minimum height. The shoe 131 is suitably mounted on

40 the bar 84 for vertical movements relative to the bar 84.

45

50

55

60

65

70

75

thereto, and suitable spring means is provided to urge said shoe constantly downwardly. In this connection and as illustrated in the drawings, bolts 133 extend loosely through openings in the top wall of the shoe 131 and are threaded into the bar 84, whereby said shoe is mounted on said bar for vertical movements relative thereto, and compressed spiral springs 134 encircle said bolts and are interposed between the heads of the latter and the top wall of said shoe whereby they react from said bolt heads upon said top wall to urge the shoe constantly downwardly. In any event, the front end portions of the under faces of the flanges 132 either are suitably rounded, or are inclined upwardly and forwardly, so that the advancing cartons pass beneath said flanges and raise the shoe 131 against the spring force exerted downwardly thereon. Consequently, during the time that containers being inserted into the cartons are exerting upward flexing force upon the end portions of the carton top walls, the cartons effectively are held by the shoe flanges 132 against any upward movement relative to the pocket elements 24 so that any danger of the bottom portions of the containers engaging the ends of the bottom walls of the cartons and crushing said bottom walls inwardly is effectively avoided.

While gravity might be relied upon to cause the filled cartons A to slide from the pocket elements 24 as the latter, during their downward travel around the rear sprocket wheel 22, reach downwardly and rearwardly inclined positions, means preferably is provided at the rear end of the machine to positively eject the filled cartons from said pocket elements. While this means may be of any suitable form, it is illustrated in Figures 3, 23 and 24 of the drawings as comprising a pair of arms 135 disposed at opposite sides, respectively, of the path of travel of the pocket elements 24 around the sprocket wheel 22, and each suitably pivoted at one end, as indicated at 136, to the related main frame side plate at a point suitably spaced downwardly and forwardly with respect to the rear shaft 29.

The arms 135 extend, generally speaking, upwardly and rearwardly from their pivot points 136, and they are sufficiently spaced outwardly with respect to the sides of the pocket elements 24 so that they are disposed beyond the paths of travel of the end containers of filled cartons in said pocket elements. At their free ends, however, said arms are provided with pins 137 which extend inwardly into the paths of travel of the end containers of filled cartons in the pocket elements. In this connection, the lengths of the arms 135 and the locations of their pivots 136 are such that by swinging said arms downwardly and rearwardly in properly timed relationship to downward travel of each pocket element 24 around the rear sprocket wheel 22, the pins 37 may be caused to engage the outer, bottom portions of the two end containers of a filled carton in the pocket element and to move downwardly and outwardly with respect to the pocket element so as to effect positive ejection of the filled carton from the pocket element.

Suitable means is, of course, provided to swing the arms 135 downwardly and rearwardly in properly timed relationship to travel of the pocket elements 24 downwardly with respect to the sprocket wheel 22, so that the pins 137 are effective to positively eject filled cartons from said pocket elements as the latter successively move to downwardly and rearwardly inclined positions. Moreover, said arm swinging means is,

of course, effective, following ejection of each filled carton from its pocket element 24 and before the next filled carton has advanced to a position to interfere with return swinging movement of the arms 135, to return said arms quickly to their upper, starting positions from which they are downwardly and rearwardly swingable to eject the said next filled carton from its pocket element.

Appropriately the means for swinging the arms 135 may comprise a cam wheel 138 fixed with respect to the sprocket wheel 22 for rotation with the latter and having a cam channel 139 of suitable form in which operates a suitable cam follower 140, such as a roller, on an arm 141 of a bell-crank lever 142 which is suitably pivoted, as indicated at 143, upon one of the main frame side plate spacing rods, for example, and which includes other, companion arms 144 connected by links 145 to the arms 135, respectively. Thus, as the cam wheel 138 rotates, it rocks the bell-crank lever 142 and thereby swings the arms 135 to cause the pins 137 to perform their function of ejecting filled cartons from the successive pocket elements 24 as the latter assume downwardly and rearwardly inclined positions during their travel around the sprocket wheel 22.

In the event of failure of supply of containers to any one or more of the container magazines, or if, for any other reason, the machine should fail to fill cartons delivered to the pocket elements 24, it would be undesirable to have the machine continue in operation. Accordingly, means preferably is provided to automatically stop the machine in such event should an attendant not notice the failure and stop the machine manually. This means (see Figures 1 to 3, 5 and 22) may be of any suitable form and, as illustrated in the drawings, comprises a pair of downwardly and rearwardly extending feeler arms 146 which are disposed above the first portions of the downward and rearward paths traveled by the end containers, respectively, of filled cartons in the pocket elements 24 as the latter move downwardly and rearwardly over the sprocket wheel 22 and which are suitably independently pivoted at their upper ends, as indicated at 147, upon, for example, a suitable bracket 148 secured to the rearmost cross member 85, for independent vertical, swinging movements. Said feeler arms are designed to rest upon the tops of such containers and to thus be maintained in elevated positions as long as such containers are present in filled cartons in the pocket elements 24, and to that end said arms have their under edges curved to correspond to the arcs traveled by the tops of the said end containers and are of lengths to span the distance between the end containers of filled cartons in adjacent pocket elements 24 so that before the end containers of a filled carton in any given pocket element 24 have moved beyond the free, lower, rear ends of said arms, the end containers of a filled carton in the next adjacent forwardly disposed pocket element will have moved beneath said arms to prevent them from dropping from their elevated positions. However, in the absence of an end container from either end of any given carton, or in the absence of end containers from both ends of any given carton, one or the other, or both, of the arms 146 is, or are, free to drop and does so either solely under the influence of gravity or, if desired, additionally under the in-

fluence of suitable spring means. In any event, each feeler arm 146 has suitably fixed with respect thereto a switch actuating arm 149 which cooperates in any suitable manner, as through a pivoted lever 150, with an electric switch 151, mounted, for example, upon the bracket 148, to control closing and opening of said switch responsive to elevation and dropping, respectively, of either of said feeler arms. In other words, as long as filled cartons in the pocket elements 24 travel downwardly and rearwardly over the rear sprocket wheel 22, the end containers of the cartons maintain the feeler arms 146 elevated and the switch 151 is closed. In the absence, however, of a container from either end of a carton as it moves downwardly and rearwardly over the rear sprocket wheel 22, one or the other of the feeler arms 146 drops downwardly and thereby acts to open the switch 151. The switch 151 controls the motor 62. Hence, said motor and the machine are automatically stopped in the event of failure of the machine to fill the cartons with containers.

Since failure of the machine to feed a carton, or cartons, and containers to any one or more of the pocket elements 24 would not result in an imperfect package, and since, for one reason or another, there might be times during operation of the machine when the feeding of both cartons and containers to one or more of the pocket elements 24 might temporarily be interrupted, it might, under such conditions, be undesirable to permit the feeler arms 146 to drop and automatically stop the machine. Accordingly, means may be provided for operation in the absence of a carton, or cartons, from any one or more of the pocket elements 24 to maintain the feeler arms 146 elevated, even in the absence of containers for that purpose. This means may be of any suitable form and in the drawings is illustrated as comprising a pair of feeler arms 152 which have the same general shape as the feeler arms 146, extend contiguously to the latter, respectively, and, like said feeler arms 146, are independently pivoted at their upper ends, as indicated at 153, to the bracket 148 for vertical swinging movements. Said feeler arms 152 overlie the upper portion of the path of travel of the pocket elements 24 downwardly and rearwardly over the sprocket wheel 22 and are designed to rest upon the tops of cartons in the pocket elements 24 and to thus be maintained in elevated positions as long as cartons are present in said pocket elements. In the absence of a carton from any given pocket element 24, however, said feeler arms 152 are designed to drop either under the influence of gravity alone, or, if desired, under the influence of gravity assisted by suitable spring means, and in order to permit said arms to drop the rear and front walls of the pocket elements 24 have therein and opening through their tops, slots 154 of suitable depths into which said arms may move.

The feeler arms 152 are related to the feeler arms 146, respectively, and on each feeler arm 146 is a stop lug 155 for cooperation with a stop finger 155' projecting from the related feeler arm 152. In this connection, the arrangements of the stop lugs 155 and the stop fingers 155' relative to the feeler arms 146 and 152, respectively, are such that when the feeler arms 152 are elevated the stop fingers 155' are disposed out of the paths of swinging movements of the stop lugs 155 with the feeler arms 146 and, therefore, do not inter-

fere with dropping of said feeler arms 146 from their elevated positions. Additionally, however, the relative arrangements of said stop lugs and said stop fingers are such that upon dropping of the feeler arms 152, the stop fingers 155' are swung into the paths of swinging movements of the stop lugs 155 with the feeler arms 146 and thereby prevent said feeler arms 146 from dropping from their elevated positions.

The free ends of the feeler arms 152 are disposed sufficiently upwardly or forwardly of the free ends of the feeler arms 146 so that as a pocket element 24 with a filled carton therein is about to move beyond the free ends of said arms and an empty pocket element moves beneath said arms, the feeler arms 152 become free to drop while the feeler arms 146 still are held elevated. Thus, in the absence of a carton and containers from any given pocket element 24 as the latter travels beneath the feeler arms 146 and 152, the feeler arms 152 drop and by so doing serve to prevent the feeler arms 146 from dropping and opening the switch 151. Therefore, in the absence of both a carton and containers from any given pocket element 24, the switch 152 remains closed and the machine continues in operation.

In some instances the end walls of the containers B are not bulged outwardly, or are only so slightly bulged outwardly as not to prevent the free edges of the carton tongues 14 from engaging the container chimes b at their bases, even though said tongues 14 may be perfectly flat. Accordingly, in such instances, the tongues 14 may be perfectly flat. In other instances, however, the end walls of the containers B may be bulged outwardly such amounts as to prevent the free edges of the tongues 14 from engaging the container chimes at their bases if the tongues 14 are perfectly flat (see Figure 32 of the drawings). In that event, particularly if the inner faces of the container chimes are inclined outwardly, as usually is the case, there exists the possibility that the tongues 14 may spring outwardly and become disengaged from the container chimes with consequent failure of the package to maintain the containers in assembly with each other. If, however, the tip portions 14a of the tongues 14 are bent so as to be inclined inwardly relative to the tongues proper when the tongues are infolded, they will engage the chimes b at the bases thereof even though the end walls of the containers may be materially bulged outwardly. Moreover, if the said tip portions 14a are inclined as stated relative to the tongues proper, there is practically completely avoided any possibility of said tip portions ever becoming accidentally disengaged from the container chimes. Accordingly, the present machine may, if desired, be designed to include means for bending the tip portions 14a of the tongues 14 so that in packages as produced by the machine the said tip portions are inclined inwardly relative to the tongues proper for most effective locking cooperation with the container chimes as shown in Figure 33 of the drawings.

To include means for the purpose stated in a machine otherwise generally the same as the machine heretofore described, involves, primarily, lengthening of the main frame of the machine sufficiently to afford space adjacent to the front end of said main frame wherein to install said means and, secondarily, in making such other alterations in the machine as heretofore described as may be necessitated by installation of said means.

Figures 25 to 30 of the drawings illustrate the

front portion of a machine which, generally speaking, is the same as the machine heretofore described, but which has incorporated therein means for bending the carton tongues 14 to incline their tip portions 14^a relative to their main body portions.

In Figures 25 to 30 the same reference characters, with the exponent ^a, are used to designate parts which correspond to parts heretofore described in connection with the machine illustrated in Figures 1 to 24 of the drawings. Thus, it will be noted that the machine illustrated in Figures 25 to 30 includes a main frame F^a, composed of spaced side plates 15^a and 16^a; a housing H^a mounted on said main frame at the front thereof and understood to contain mechanism as heretofore described for pushing cartons successively from the bottom of a stack in a magazine M^a mounted on said housing H^a and for delivering the cartons to pocket elements 24^a as the latter reach upwardly and forwardly inclined positions in their travel around a front shaft 19^a; upper and lower cam plates 97^a, 98^a, respectively, for turning the carton tongues to positions at right angles to the carton top and bottom walls as the cartons are advanced with the pocket elements 24^a, and fingers 119^a for inturning the tongues of the carton bottom walls into overlying relationship to the carton bottom walls.

In the machine illustrated in Figures 25 to 30, the cam plates 97^a, 98^a are not mounted on the arcuate member 83^a and the track members 28^a, respectively, as in the machine illustrated in Figures 1 to 24, but are mounted rearwardly of the front shaft 19^a on brackets 156 fixed to and rising from the main frame side plates. Said cam plates therefore operate after the pocket elements 24^a have completed their travel around the front shaft 19^a and while said pocket elements are traveling rearwardly with the upper reach of the sprocket chain 23^a, to turn the carton tongues 14 to positions at substantially right angles to the carton top and bottom walls. Thus, said cam plates 97^a, 98^a are generally straight instead of curved as in the machine illustrated in Figures 1 to 24, but otherwise are generally the same as the cam plates 97 and 98.

In the machine as illustrated in Figures 25 to 30, the means, designated generally as C, for bending the tips 14^a of the carton tongues, is located forwardly of the cam plates 97^a, 98^a so as to accomplish its purpose while the carton tongues still extend outwardly from the carton top and bottom walls in the planes of the latter.

The means C comprises right and left hand mechanisms which are mounted in the main frame side plates 15^a and 16^a, respectively, at opposite sides of the path of travel of the pocket elements 24^a with the upper reach of the sprocket chain 23^a, and which are operable, one to bend the tongue tips at one end of each carton, and the other to bend the tongue tips at the other end of each carton, as the cartons are advanced with the pocket elements 24^a.

The said mechanisms are right and left hand duplicates of each other. Therefore, a description of one will suffice for both. Accordingly, referring to either of said mechanisms, the same comprises a suitable frame 157 which is suitably fastened to the related main frame side plate and which has journaled therein upper and lower shafts 158 and 159, respectively, which are disposed horizontally and which extend transversely of the machine.

On the inner ends of the shaft 158 and 159

75 portions are inclined inwardly relative to the

are rollers 160 and 161, respectively, which are disposed at elevations such that, as the cartons A are advanced with the pocket elements 24^a, the outwardly extending upper and lower tongues 14 at the related end of each carton pass directly above and directly below said rollers, respectively.

Above and below the shafts 158 and 159 are shafts 162 and 163, respectively, which also extend transversely relative to the machine and which carry at their inner ends rollers 164 and 165, respectively, which overlie and underlie the rollers 160 and 161, respectively.

The shafts 162 and 163 are journaled in upper and lower blocks 166 and 167, respectively, which are suitably pivoted to the frame 157, as indicated at 168 and 169, respectively, so that said shafts 162 and 163 are vertically swingable to permit the rollers 164 and 165 to move toward and away from the rollers 160 and 161, respectively. Moreover, suitable springs 170 and 171 suitably react from the frame 157 upon the blocks 166 and 167, respectively, so as to tend constantly to swing said blocks in directions to urge the rollers 164 and 165 toward the rollers 160 and 161, respectively.

Since the carton tongues pass directly above and directly below the rollers 160 and 161, they pass, of course, between the upper and lower pairs of rollers 160, 164 and 161, 165, respectively, and since the rollers 164 and 165 are constantly spring urged toward the rollers 160 and 161, respectively, the carton tongues are firmly gripped between said upper and lower pairs of rollers as they pass therebetween.

The outer faces of the rollers 160, 161, 164 and 165 are disposed in a common plane, and the rollers 160 and 161 have integral therewith, or fixed thereto, at their outer sides, flange sectors 172 and 173, respectively, which, by rotation of said rollers 160 and 161, are movable into overlapping relationship to the outer faces of the rollers 164 and 165, respectively.

The spacing of the outer faces of the rollers 160, 161, 164 and 165 from the sides of the pocket elements 24^a is such that when the upper and lower carton tongues 14 pass between the upper and the lower pairs, respectively, of said rollers, suitable length tip portions 14^a of said tongues extend outwardly beyond the outer faces of said rollers. The inner faces of the flange sectors 172 and 173 are spaced outwardly with respect to the outer faces of the rollers 164 and 165 by amounts substantially equal to the thickness of the carton tongues 14. Hence, rotation of the rollers 160 and 161 and moving of their flange sectors 172 and 173 into overlapping relationship to the rollers 164 and 165, respectively, as the carton tongues 14 advance between the upper and lower pairs of rollers, results in the tip portions 14^a of the upper and lower carton tongues 14 being bent upwardly and downwardly, respectively, across the outer faces of the rollers 164 and 165, respectively, by the flange sectors 172 and 173, respectively. In this connection, the outer faces of the rollers 164 and 165 and the coacting inner faces of the flanges 172 and 173 may be formed as desired so that the tip portions 14^a of the tongues 14 are bent to positions either at right angles or at any desired inclinations relative to said tongues. In any event, said tongue tip portions are sufficiently bent so that when the tongues subsequently are completely inturned into the cartons, said tip

70 portions are inclined inwardly relative to the

tongues so as to engage at their free edges with the chimes *b* of containers *B* at the bases of said chimes, as illustrated in Figure 33 of the drawings, even though the container end walls are more or less bulged outwardly.

On the outer ends of the shafts 158 and 159 are spur gears 175 and 176, respectively, while on the outer ends of the shafts 162 and 163 are spur gears 177 and 178, respectively, which mesh with the spur gears 175 and 176, respectively. Moreover, on the shafts 158 and 159 are spur gears 179 and 180, respectively, which mesh with each other. One of the shafts 158 or 159 is suitably driven and therefore both pairs of the tip bending rollers are driven. In this connection, the driving of the said pairs of tip bending rollers is in such timed relationship to advance of the cartons with the pocket elements 24^a that there is a true rolling action and no wiping action between the tip bending rollers and the carton tongues.

Appropriately, a sprocket chain 181 may connect a sprocket wheel 182 on the shaft 158 with a sprocket wheel 183 suitably driven in harmony with the pocket elements 24^a whereby the pairs of tip bending rollers are driven in properly timed relationship to advance of the pocket elements 24^a. In this connection, the disposition of the flange sectors 172 and 173 is such that they do not act upon the carton tongues to bend the tips thereof until after said tongues have entered between the pairs of rollers 160, 164 and 161, 165, respectively. Preferably the frames 157 carry suitable means, designated generally as 184, to guide the carton tongues 14 between the pairs of rollers 160, 164 and 161, 165.

The front ends of the cam plates 97^a, 19^a are disposed directly rearwardly of the means *C* so as to begin to act upon the carton tongues to turn the latter to positions at substantially right angles to the carton top and bottom walls immediately following bending of the tongue tips by said means *C*. In other respects the machine illustrated in Figures 25 to 30 of the drawings is, or may be, generally the same as the machine illustrated in Figures 1 to 24 of the drawings.

From the foregoing description considered in connection with the accompanying drawings, it is believed that the construction and mode of operation of the present machine will be clearly understood and that its advantages will be appreciated. It is desired to point out, however, that while only certain specific structural embodiments of said machine have been illustrated and described, the same is readily capable of various other specifically different structural embodiments within the spirit and scope of the invention as defined in the appended claims.

We claim:

1. A machine for filling cartons of the open-ended type with containers, said machine comprising means for advancing the cartons along an endless path, a plurality of fixed rails constituting container guide means extending along the sides of said path, means for feeding containers to said guide means, and means for advancing the containers along said guide means individually in alinement with the open ends of said cartons as the latter are advanced, said rails being formed for operation in response to advance of the cartons and the containers to urge the containers first cornerwise into the cartons through their open ends and finally into the cartons to positions parallel to the ends of the latter.

2. A machine for filling cartons of the open-

ended type with containers, said machine comprising means for advancing the cartons along an endless path, a plurality of fixed rails constituting container guide means extending along a side of said path, means for feeding containers to said guide means, and means for advancing the containers along said guide means individually in alinement with an open end of each carton, said rails being constructed and arranged for operation in response to advance of the cartons and the containers first to insert a corner of each container into its related carton through an open end thereof adjacent to one of the top and the bottom walls of the carton, then to move the container endwise toward said wall so as to engage and deflect the end portion of said wall outwardly, and then to urge the container into the carton to a position parallel to the ends of the carton.

3. A machine for filling cartons of the open-ended type with containers, said machine comprising an endless series of pocket elements movable along an endless path, means for feeding cartons to said pocket elements as the latter are advanced along said path, container guide means extending along the sides of said path, means for feeding containers to said guide means, and means carried by said pocket elements for engagement with containers fed to said guide means to advance the containers along said guide means in alinement with the open ends of the cartons, respectively, said guide means including rails inclined to urge the containers into the cartons through their open ends in response to advance of the cartons and the containers.

4. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising means for advancing the cartons along a definite path initially with their tongues projecting outwardly from the ends of their top and bottom walls, means operable as said cartons are advanced to inturn said tongues, stationary container guide means extending along the sides of said path, means for feeding containers to said guide means, and means for advancing the containers along said guide means individually in alinement with the open ends of said cartons as the latter are advanced, said guide means having portions thereof inclined relative to said path to urge the containers into the cartons through the open ends of the latter in response to advance of the cartons and the containers following inturning of said tongues.

5. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising means for advancing the cartons along a definite path initially with their tongues projecting outwardly from the ends of their top and bottom walls, stationary cam rail means operable in response to advance of said cartons to inturn said tongues, means for advancing the containers along said path individually in alinement with the open

ends of said cartons as the latter are advanced, and stationary means also operable in response to advance of said cartons and the containers following inturning of said tongues to insert the containers into the cartons through their open ends.

6. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising means for advancing the cartons along a definite path initially with their tongues projecting outwardly from the ends of their top and bottom walls, stationary cam rail means operable in response to advance of said cartons to partly inturn said tongues, other means operable as the cartons are advanced to completely inturn the tongues of one of the carton walls to facilitate entrance of containers into the cartons through their open ends, means for advancing the containers along said path individually in alignment with the open ends of the cartons, and stationary means operable following complete inturning of the tongues of said one of said carton walls and in response to continued advance of the cartons and the containers to insert the containers into the cartons through their open ends.

7. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising means for advancing the cartons along a definite path initially with their tongues projecting outwardly from the ends of their top and bottom walls, stationary cam rail means operable in response to advance of said cartons to partly inturn said tongues, reciprocable finger means operable as the cartons are advanced to completely inturn the tongues of one of the carton walls to facilitate entrance of containers into the cartons through their open ends, means for advancing the containers along said path individually in alignment with the open ends of the cartons, and stationary means operable following complete inturning of the tongues of said one of said carton walls and in response to continued advance of the cartons and the containers to insert the containers into the cartons through their open ends.

8. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising means for advancing the cartons along a definite path with their open ends disposed at the sides of said path and with said tongues initially projecting outwardly from said top and bottom walls, means operable as said cartons are advanced to inturn said tongues, container guide means extending along the sides of said path, means for feeding containers to said guide means, and means for advancing containers along said guide

means in alignment individually with the open ends of said containers, said guide means being stationary and having portions thereof inclined to urge the containers into the cartons through the open ends of the latter in response to advance of the cartons and the containers following inturning of the tongues of the latter.

9. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising means for advancing the cartons along a definite path with their open ends disposed at the sides of said path and with said tongues initially projecting outwardly from said top and bottom walls, means operable as said cartons are advanced to inturn said tongues, container guide means extending along the sides of said path, means for feeding containers to said guide means, and means for advancing containers along said guide means in alignment individually with the open ends of said containers, said guide means each including a plurality of rails certain of which are inclined to urge the containers into the cartons through the open ends of the latter in response to advance of the cartons and the containers following inturning of the tongues of the latter and other of which are inclined to tilt the containers so that they are caused to enter the cartons first cornerwise and finally in positions parallel to the ends of the cartons.

10. A machine for filling cartons of the open-ended type with containers of the type having chimes at their ends, the top and the bottom walls of the cartons having at their ends tongues to be inturned for engagement at their free edges with the chimes of the two end containers of a row in a carton to retain the containers in the carton, said machine comprising an endless series of pocket elements movable along an endless path, means for feeding to said pocket elements during their travel along said path cartons in open condition with their tongues extending outwardly from the ends of their top and bottom walls, cam means operable in response to advance of said cartons to turn said tongues inwardly into substantially right angular relationship to said top and bottom walls, reciprocable elements cooperable with said pocket elements following said inturning of said tongues to further inturn the tongues of the carton bottom walls into overlying relationship to said bottom walls, container guide means extending along the sides of said path, means for feeding containers to said guide means, and means for advancing said containers along said guide means simultaneously with said cartons and in alignment with the open ends of the latter, said guide means including plural rails certain of which are inclined to urge the containers into the cartons and others of which are inclined to tilt the containers to cause them to enter the cartons first cornerwise adjacent to the top walls of the cartons and finally in positions parallel to the ends of the cartons.

11. A machine for filling cartons of the open-ended type with containers, said machine comprising an endless series of open-sided pocket elements movable along an endless path with their open sides disposed at the sides of said path, means for feeding cartons to said pocket ele-

ments with the open ends of the cartons disposed adjacent to the open sides of said pocket elements, container guide means extending along the sides of said path, means for feeding containers to said guide means, and arms carried by said pocket elements and projecting beyond their sides to engage the containers and push them along said guide means individually in alinement with the open ends of said containers, said guide means including rails inclined to urge the containers into the cartons responsive to advance of the cartons and the containers along said path and along said guide means, respectively.

12. A machine for filling cartons of the open-ended type with containers of the type having chimes at their ends, the top and the bottom walls of the cartons having at their ends tongues to be inturned for engagement with the chimes of the two end containers of a row in a carton to retain the containers in the carton, said machine comprising a magazine to contain a stack of the cartons in substantially flat collapsed condition with the tongues thereof extending outwardly from the ends of the carton top and bottom walls, an endless series of pocket elements movable in an endless path, means for transferring the cartons individually from said magazine to said pocket elements, respectively, and for setting them up in open condition in said pocket elements as the latter are advanced along said path, means operable during advance of said pocket elements along said path to bend the tip portions of said tongues relative to the base portions of said tongues to adapt said tip portions to engage the container chimes adjacent to the bases of the latter when said tongues are inturned and containers are inserted into the cartons, means thereafter operable during advance of said pocket elements to inturn said tongues, and means subsequently operable during advance of said pocket elements to insert containers into the cartons through their open ends.

13. In a machine of the character described, a magazine to contain a stack of cartons in substantially flat collapsed condition, means for engaging the lowermost carton of the stack and flexing it downwardly medially from the carton immediately thereabove, a reciprocable blade projectable between said lowermost carton and the carton immediately thereabove to separate said lowermost carton from the cartons thereabove and to support the cartons thereabove during removal of the lowermost carton from the stack, and a reciprocable bar separate from said blade projectable relative to said blade to push the lowermost carton of the stack from the stack.

14. In a machine of the character described, a plurality of pocket elements each open at its sides and top and closed at its front and rear and bottom and movable along an endless path including a horizontal course, means for feeding to said pocket elements as they advance along said path open-ended cartons with the open ends of the cartons disposed adjacent to the open sides of said pocket elements, container guide means extending along the sides of the horizontal course of said path, means for feeding containers to said guide means, and arms projecting from the sides of the rear walls of said pocket elements to engage containers fed to said guide means and to advance them along said guide means individually in alinement with the open ends of the cartons contained in said pocket elements, said guide means including rails inclined to urge the containers into the cartons through the open

ends of the latter responsive to advance of the pocket elements and the containers.

15. In a machine for filling cartons of the open-ended type with containers, an open-top, open-sided pocket element closed at its front, rear and bottom to contain an open-ended carton with the open ends of the carton disposed adjacent to the open sides of said pocket element, means for moving said pocket element along a substantially horizontal path, a bar extending along said path above said pocket element to hold the container in said pocket element, container guide means extending along the sides of said path, means to move containers along said guide means with said pocket element and in alinement with the open ends of a carton contained in said pocket element, said guide means including inclined rail means to urge the containers into the carton in response to advance of the pocket element and the containers along said path and along said guide means, respectively, said guide means including other rail means operable first to tilt the containers to cause them initially to enter the carton cornerwise at their upper corners, then to raise the containers to flex the end portions of the top wall of the carton upwardly to afford clearance between the bottom wall of the carton and the bottoms of the containers, and finally to tilt the containers to positions parallel with the ends of the carton as the bottom portions of the containers are urged into the carton, and means to maintain downward pressure upon the medial portion of the top wall of the carton during raising of the containers to prevent the bottom wall of the carton from being raised due to upward flexing of the end portions of the top wall of the carton.

16. The combination of elements as set forth in claim 15 in which the means to maintain downward pressure upon the medial portion of the top wall of the carton comprises a member carried by the bar for downward movement below the latter to engage the top wall of the carton, and spring means constantly effective to urge said member downwardly.

17. The combination of elements as set forth in claim 15 in which the means to maintain downward pressure upon the medial portion of the top wall of the carton comprises a member of inverted U-shape in cross section superimposed upon the bar and having side flanges extending contiguously to the sides of the bar and projectable below the bar to engage the top wall of the carton, means mounting said member upon the bar for vertical movement relative thereto, and spring means constantly urging said member downwardly relative to the bar to project said flanges below the latter.

18. A machine as set forth in claim 12 in which the means to bend the tip portions of the carton tongues comprises cooperating pairs of rollers between which the tongues pass during advance of the cartons, one roller of each pair having a flange for cooperation with the other roller of the pair to effect the bending.

19. A machine as set forth in claim 3 including means separate from said pocket elements for ejecting the filled cartons from the pocket elements.

20. A machine as set forth in claim 3 including means operable to stop the machine in the absence of a container from either end of any carton when the latter reaches a predetermined point in its travel.

21. A machine as set forth in claim 3 includ-

ing means operable to stop the machine in the absence of a container from either end of any carton when the latter reaches a predetermined point in its travel, and means operable to nullify the action of said machine stopping means in the absence of a carton from any given pocket when said pocket reaches said predetermined point in its travel.

22. A machine for inserting containers into cartons, said machine comprising means for advancing the cartons along a definite path with at least one end of each carton open and facing a side of said path, container guide means extending along said side of said path, means for feeding containers to said guide means, means for advancing the containers along said guide means individually in alinement with the open ends of said cartons as the latter are advanced, said guide means being stationary and having a portion thereof inclined inwardly relative to said path in the direction of advance of the cartons and the containers to urge the containers into the cartons in response to advance of the cartons and the containers.

23. A machine for inserting containers into cartons, said machine comprising means for advancing the cartons along a definite path with at least one end of each carton open and facing a side of said path, container guide means extending along said side of said path, means for feeding containers to said guide means, means for advancing the containers along said guide means individually in alinement with the open ends of said cartons as the latter are advanced,

said guide means being stationary and having different portions thereof differently inclined relative to said path so as initially to urge the containers cornerwise into the cartons, then to move the containers endwise relative to the cartons to facilitate entering of the containers into the cartons, and finally to urge the containers into the cartons to positions parallel to each other and parallel to the ends of the cartons, all in response to advance of the containers and the cartons.
